CLAIM

I claim the ornamental design for an operating and connection unit for a standing umbrella, as shown and described.

DESCRIPTION

FIG. 1 is a side elevation view of an operating and connection unit for a standing umbrella showing my new design in the condition of use

FIG. 2 is a front elevation view of the operating and connection unit shown in FIG. 1.

FIG. 3 is a rear elevation view of the operating and connection unit shown in FIG. 1.

FIG. 4 is a right side elevation view of the operating and connection unit shown in FIG. 1.

FIG. 5 is a left side elevation view of the operating and connection unit shown in FIG. 1.

FIG. 6 is a top plan view of the operating and connection unit shown in FIG. 1; and,

FIG. 7 is a bottom plan view of the operating and connection unit shown in FIG. 1.

The broken lines in FIG. 1 represent the environmental subject matter. The broken lines in FIG. 5 are included for the purpose of illustrating the portions of the operating and connection unit that form no part of the claimed design. None of the broken lines form a part of the claimed design.
